(57) **CLAIM**

The ornamental design for outdoor cabinet with surface ornamentation, as shown and described.

DESCRIPTION

FIG. 1 is a front perspective view of an outdoor cabinet with surface ornamentation illustrating an embodiment of our new design;

FIG. 2 is a front view thereof;

FIG. 3 is a rear view thereof;

FIG. 4 is a left view thereof;

FIG. 5 is a right view thereof;

FIG. 6 is a top view thereof; and

FIG. 7 is a bottom view thereof;

In FIGS. 1 and 6, the stippling indicates a contrast in texture, where the heavier stippling may have a different texture than the lights stippling, or may have the same texture as the lighter stippling.

FIG. 8 is a front perspective view of an outdoor cabinet with surface ornamentation illustrating an embodiment of our new design;

FIG. 9 is a front view thereof;

FIG. 10 is a rear view thereof;

FIG. 11 is a left view thereof;

FIG. 12 is a right view thereof;

FIG. 13 is a top view thereof; and,

FIG. 14 is a bottom view thereof.

In FIGS. 8 and 9, the stippling indicates a contrast in texture, where the heavier stippling may have a different texture than the lights stippling, or may have the same texture as the lighter stippling.

The dash-dash broken lines in the drawings are included for the purpose of illustrating portions of the outdoor cabinet with surface ornamentation and the dash-dot-dot broken lines in the drawings depict the bounds of the claimed design. All broken lines form no part of the claimed design.
